UNITED STATES PATENT OFFICE.

MAXIMILIAN CHARLES SCHWEINERT, OF WEST HOBOKEN, NEW JERSEY, AND HENRY P. KRAFT, OF NEW YORK, N. Y., ASSIGNEES, BY MESNE ASSIGNMENTS, TO A. SCHRADER'S SON, INCORPORATED, OF NEW YORK, N. Y., A CORPORATION OF NEW YORK, (INCORPORATED IN 1906.)

TIRE-VALVE.

1,050,491.

Specification of Letters Patent.

Patented Jan. 14, 1913.

Application filed May 26, 1906. Serial No. 318,902.

To all whom it may concern:

Be it known that we, MAXIMILIAN CHARLES SCHWEINERT, residing at West Hoboken, in the county of Hudson and State 5 of New Jersey, and HENRY P. KRAFT, residing in the borough of Brooklyn, county of Kings, city and State of New York, citizens of the United States, have jointly invented certain new and useful Improvements in 10 Tire-Valves, of which the following is a specification.

In tire valves of the usual Schrader and similar types, the valve seats against what we may call a seat member, and this seat member is removable from within the casing. The present invention provides an improved device for securing a tight joint between the seat member and the casing, so that no air shall leak around the seat member. For this purpose we provide a packing which is arranged to be expanded laterally, preferably by the axial pressure which is used in inserting the seat member to its position within the casing.

25 Various advantages are referred to in detail hereinafter.

The accompanying drawings illustrate embodiments of the invention.

Figure 1 is a diametral section through the casing of a valve showing the internal parts in elevation; Figs. 2 and 3 illustrate on a larger scale the action of the packing, being diametral sections through the seat member in different positions of the latter; 35 Figs. 4 and 5 are diametral sections of other forms of the invention.

Referring to the embodiments of the invention illustrated, the seat member A has its lower end formed into a valve seat for engagement by the valve B. The seat member is forced into place or withdrawn by means of a threaded plug C, which is swiveled to the seat member, as indicated in the sectional views. In many previous valves 45 of this type the movement of the seat member into the casing served to bring a packing ring on the seat member against a wall of the casing to effect the required tight joint, the packing ring being pressed inward or upward by its engagement with the wall of

the casing. According to the present invention the seat member is brought to its position in the casing, and the packing is then expanded to fill the space around a certain line between the seat member and the casing. 55 Preferably this expansion is effected by a further axial movement of the plug after the seat member has found its position in the casing. An important feature of the invention is that the packing is expanded 60 without being subjected to any material torsional action, so that it is not distorted thereby. The packing ring is arranged between a suitable shoulder of the seat member and a lower face of the plug, and is made of very 65 yielding and elastic material, such as good rubber, so as to permit of the desired lateral expansion under axial pressure. In the construction illustrated for example, the casing is provided with a shoulder D of suitable 70 diameter to engage the tapered under face of the seat member A, and to stop the latter at the desired height in the casing. Surrounding the seat member A and resting upon a shoulder E thereof, is a ring F of 75 rubber or the like, which may be of circular section as shown, or of any other convenient section. After the seat member A has found its position against the shoulder D of the casing, the further downward movement of the plug C brings a pressure against the upper edge of the packing ring F, and spreads the latter in the manner indicated in Fig. 3, so that it presses hard at all points against the casing around a line G, and 80 makes an air-tight closure around this line. In previous constructions in which the seat member was moved down until its packing ring pressed sufficiently hard upon the shoulder of the casing to prevent further 85 movement of the seat member, and at the same time to make a tight joint between the seat member and the casing, the packing was often damaged in the first introduction of the seat member into the casing. 90 Furthermore the packing often by being pressed too hard against the casing, stuck to the latter when the seat member was withdrawn, thus ripping off the packing and requiring renewal. In the present case the 95 100

principal pressure against the packing ring is that of the parts above and below it, which are movable with it, and which therefore if there is any sticking, will not cause a rip-
6 ping of the packing off the seat member.

In order to avoid the friction of turning the plug C directly upon the packing ring F, which might injure the latter, we preferably provide an anti-friction ring H between the 10 plug and the packing ring, this anti-friction ring being of metal and preferably circular in cross-section. Now when the plug is rotated, it will move freely over the upper edge of the antifriction ring H, while the 15 latter will remain stationary against the packing ring F. It will be noted that as the seat member is pressed inwardly it has no substantial rotary motion. This is important since as the packing ring is com-
20 pressed its inner side presses against the seat member, and if the latter were rotated as it was pressed inwardly it would tend to produce a certain degree of torsional distortion in the packing.

25 The principle may be embodied in a great number of variations of which we have shown only a few. For example in Fig. 4 the loose ring J comes to a stop against the shoulder D of the casing, while the move-
30 ment of the remaining portions of the seat member and plug squeezes the packing ring F between the ring J and a shoulder K above. A similar construction is shown in Fig. 5, a ring L being arranged to engage 35 the shoulder D of the casing, and to squeeze the packing ring F in the same manner as in Fig. 4; the ring L however being clamped about an inner extension M of the packing ring so as to prevent the latter in any case
40 from being drawn over the end of the seat member when the latter is withdrawn from the casing. The shouldered portion K of the seat member in this construction, as well as in that in Fig. 4, serves also as an anti-
45 friction ring between the packing ring and the plug C.

This invention also includes a novel method of connecting the seat member to the plug, according to which the plug is 50 formed with a flange O which is turned inwardly over a flange P formed on the seat member. Preferably, the plug is formed with a deep socket Q, which permits considerable movement of the flange of the seat
55 member therein, so that a great relative movement of the plug and seat member is provided for compressing the packing.

60 Though we have described with great particularity of detail certain specific embodiments of our invention, yet it is not to be understood therefrom that the invention is limited to the particular embodiments disclosed. Various modifications thereof in detail, and in the arrangement and combination of the parts, may be made by those

skilled in the art, without departure from the invention.

What we claim is:

1. In a valve for tires or the like, in combination, a casing, a seat-member, fitting within said casing, a packing surrounding said seat-member and fitting within said casing with said seat member and means also fitting within the casing and adapted to expand said packing laterally until its expanded edge is compressed against the inner wall of said casing and makes a tight joint therewith, said means operating without exposing said packing to any substantial rotary distortion. 70

2. In a valve for tires or the like, in combination, a casing, a seat member adapted to fit within said casing, a screw-threaded plug swiveled thereto and extending within said casing, a packing ring surrounding said seat member in said casing, and an anti-friction member also surrounding said seat member, said plug being adapted to compress said packing between said anti-friction member and said seat member to expand said packing laterally against the inner wall of said casing. 80

3. In a tire valve or the like, in combination, a casing, a seat member fitting within said casing, a screw-threaded member movable independently of said seat-member and extending within said casing and having a deep socket, and an inwardly turned flange, and said seat member extending within said socket and having an outwardly turned flange, and a packing ring surrounding said seat member within said casing and adapted to be compressed by a movement of the end of said seat member into said socket. 90

4. In a valve for tires or the like, in combination a casing, a seat member within said casing having a shoulder, a packing next said shoulder, an anti-friction ring next said packing, and means also within said casing movable independently of said seat member 100 for pressing said anti-friction ring and shoulder toward each other without imparting substantial rotary movement to said ring or seat. 105

5. In a valve for tires or the like, in combination a seat member having a metal portion adapted to engage a shoulder of the casing, a packing ring surrounding said seat member above said metal portion, and a metal portion above said packing ring, the two metal portions being movable axially toward each other to exert an axial pressure on said ring, and said ring being of elastic material adapted to expand laterally to engage the side of the casing. 115

6. In a valve for tires or the like, in combination a seat member A adapted to engage a shoulder D within the casing to limit the downward movement of the seat member, a ring of packing material surrounding said 120 130

seat member, and means for exerting an axial pressure upon said ring after said seat member has engaged said shoulder D, said ring being of rubber to expand freely 5 in a lateral direction under such axial pressure to engage the side of the casing.

In witness whereof, we have hereunto

signed our names in the presence of two subscribing witnesses.

MAXIMILIAN CHARLES SCHWEINERT.

HENRY P. KRAFT.
